UNITED STATES PATENT OFFICE.

RICHARD HENRY ANNISON, OF LONDON, ENGLAND.

PISTON-CONTROL MECHANISM.

Application filed June 23, 1920. Serial No. 391,199.

(GRANTED UNDER THE PROVISIONS OF THE ACT OF MARCH 3, 1921, 41 STAT. L., 1313.)

To all whom it may concern:

Be it known that I, RICHARD HENRY ANNISON, a subject of the King of Great Britain and Ireland, residing at London, England, have invented certain new and useful Improvements in Piston-Control Mechanism (for which I have filed application in Great Britain March 22, 1919, Patent 150,010), of which the following is a specification.

This invention relates to improved means for controlling pistons in cylinders for use in connection with pile drivers, hammers, pile extractors and the like apparatus and refers to apparatus of this kind wherein the cylinder is provided with a series of separately closable ports in communication with a valve chamber, the ports being arranged longitudinally of the cylinder so that the stroke of the piston may be varied by varying the point of exhaust from the cylinder.

The invention has for its object an improved construction of apparatus of this type and relates more particularly to special and advantageous constructions and applications of the invention to pile drivers, pile extractors, hammers, and the like apparatus.

According to the present invention, the cylinder is provided with one or more passages leading to a valve chamber through which operating fluid controlling the movement of the valve as admitted, one or each of said passages having a plurality of separately closable ports arranged longitudinally of the cylinder co-operating with one or more chambers in the periphery of the piston, whilst the cylinder is also provided with separate and independent passages leading to opposite ends of the cylinder through which operating fluid is admitted and emitted from opposite sides of the power cylinder. The steam or other motive fluid is admitted alternately at each end of the piston, and the exhaust opened at the appropriate times, in the ordinary way, the separately closable ports permitting the timing of the admission and exhaust to be varied as regards the length of the cylinder, so that the stroke of the piston can be altered and consequently the blow or other effort of the machine varied to suit requirements.

For controlling the admission and exhaust I provide any suitable valves but preferably

a semirotary valve, which alternately admits the pressure fluid to each side of the piston and opens the corresponding exhaust, the valve being automatically operated by the pressure fluid when the piston reaches each end of its stroke, which stroke may be varied as just explained.

In order that the general features of my invention may be understood I will now describe the same as applied to the piston of a pile driver or pile extractor.

The semi-rotary valve which I prefer to employ is contained in a suitable casing having inlet and outlet passages for the operating fluid. The valve comprises two discs or drums with a spindle between them, and so attached thereto that they can be readily separated and removed from the casing, the spindle being preferably of smaller diameter than the disc.

These discs or drums have a plurality of pockets or recesses in or upon part of their periphery, each balancing the other. In a similar way the edge of the periphery opposite to the pockets may be cut away or slotted to form a recess engaging with a stop or stops provided in the casing for the purpose of stopping the rotation at the desired point.

I may further provide a small passage in or across each disc from one or more of the pockets to the opposite edge to allow a small quantity of the operating fluid to cushion the shoulder of the disc or discs against the stops provided for it.

The spindle may also have two or more ports or openings through or across forming two way or three way passages. Preferably there are four through passages kept fluid tight from each other and their adjoining discs by means of piston rings or other means or combination of means. The four spindle ports lead to two bridged ways for the admission and emission of fluid to and from the passages leading to the cylinder, for the operation of the piston therein.

In the case of four ports, one each of one pair acts in concert alternately with one of the other pair and by the use of four, the admission port leading to one end of the cylinder body may be larger than the other and the ones for the exhaust varied in like manner.

The piston in the cylinder has part of its

body cut away at each end to admit the operating medium or the cylinder cover or both may be recessed for the same purpose. The intermediate portion of the piston body 5 is also cut away or recessed, forming one or more chambers between it and the cylinder wall for the supply of the operating fluid to rotate the discs through suitably placed openings or ports in the cylinder 10 wall.

The passages or conduits for the operating fluid to and from the valve disc and/or cylinder piston may be formed out of or in conjunction with the valve casing or 15 other cover upon the wall of the cylinder body or by a separate pipe or pipes provided for the purpose.

The conduit or passage or passages may be provided with taps, stops, plugs or valves 20 or any other suitable devices or combination of devices for the purpose of varying at will the point of passage of the operating fluid from the piston chamber through the cylinder or wall to the disc to be operated 25 as the piston alternately opens or closes these ports as it travels to and fro in the cylinder the distance of said travel being regulated as the tap or other devices are set or adjusted from time to time by hand or automatically. 30

In a practical application to a pile driver or extractor the piston may travel upon a central rod or rods one of them being fixed and solid and having a striking block attached to or forming part of the central rod and closing one end of the cylinder, made fluid tight by means of piston rings the other end of the rod passing through a gland in the cylinder cover at the opposite 40 end, and shock absorbing spring means may be provided upon it, suitably retained in position.

Other devices may be attached, such as 45 grips for use in lifting or the cross head of a pump or compressor.

In order that the invention may be readily understood, reference is made to the accompanying drawings, which show one construction according to the invention in 50 which:

Fig. 1 is a longitudinal section of the cylinder and piston.

Fig. 2 is a similar view showing the piston at the opposite end of its stroke.

Fig. 3 is a sectional view, on the line 3—3 of Fig. 4 showing the valve mechanism on a larger scale.

Fig. 4 is an end view of Fig. 3 partly in section.

Fig. 5 shows a modified construction in which the operating fluid is admitted to the cylinder through the central hollow rod.

Fig. 6 shows a further modification in which two hollow central rods are employed.

Fig. 7 shows a modified construction of the piston or monkey.

Fig. 8 shows a construction in which the central rod is dispensed with.

The cylinder 1 is formed with a flanged head 2 to which is bolted or otherwise secured a cover plate 3. The opposite end of the cylinder is provided with a striking or anvil block 4, a portion of which extends within the bore of the cylinder at 5, and is 75 rendered steam tight therein by one or more piston rings 6. This striking block is formed integral with or has attached thereto a rod 7 extending through the centre of the cylinder and through a gland 8 provided in the cover plate 3, a shock absorbing spring or springs 9 being provided between the top of the cylinder cover and stop 10 retained by a nut 11 screwed on to the rod 7. The outer end of the rod is preferably 80 screwed at 12, for attachment of tackle or grips when the apparatus is used for extracting piles. 85

The piston or monkey 13 is cut away at 14, to form a chamber for the passage of steam or other operating fluid from the ports 15, communicating with the inlet passage 16, whilst the ends of the piston are cut away or chamfered at 17. The piston is further provided with one or more piston 95 rings 18 between the chamber 14 and its ends. The walls of the cylinder are further provided with passages 19 and 19^a for admitting the operating fluid to the valve casing to operate the valve. One or both if desired of the passages 19 and 19^a communicates with the interior of the cylinder through a number of ports 20. Those ports are arranged at spaced intervals longitudinally of the cylinder and are each provided with separate cocks, stops, or the like 21 by means of which any of the ports may be closed as desired in order to vary the point of admission of the operating fluid to the valve casing and thus vary the stroke. The inlet passage 16 is preferably located adjacent the valve casing but is shown in Figs. 1 and 2 of the drawings on the opposite side of the cylinder for the sake of clearness. 100

Referring now to Figs. 3 and 4, the valve casing 23 is of any appropriate construction and may be formed with or separately attached to the wall of the cylinder. The valve comprises two discs or drums, 24 and 25 connected by a spindle 26. The discs are preferably so attached thereto that they can be readily separated and removed from the casing, the spindle 26 being preferably of smaller diameter than the discs. 110

The discs 24 and 25 are each formed with a plurality of pockets or recesses 27 extending around a portion of their peripheries, each balancing the other, that is, the pockets are arranged to co-operate with the operating fluid, entering through the ports 27^a in the 120 125 130

valve chamber, so as to rotate the valve in opposite directions, the portions of the periphery of said discs opposite the pockets, each being cut away or formed with a circumferential slot, 28 to form a recess engaging a stop or stops 29 secured to the casing for limiting the rotary movement of the valve. 30 is a passage across the discs extending from or communicating at one end with one or more of the pockets 27 and at the opposite end with the circumferential recess 28. This passage allows a small quantity of operating fluid to cushion the shoulder 28^a at the end of the recess 28 against the stop 29.

The spindle 26 is formed with two passages 31 and 32, extending transversely through said spindle and parallel with one another, and two similar passages 33, 34 extending at right angles to the passages 31 and 32. The passages 32 and 33 constitute ports through which steam is conveyed from the chamber 35, formed in the valve casing, said chamber being supplied with steam through a pipe or pipes not shown, secured to the inlet port 36.

The spindle 26 is rendered fluid tight within its casing by a plurality of piston rings 37, arranged between the transverse passages 31, 32, 33 and 34, and between the discs 24 and 25 and the adjacent passages 31 and 34 respectively.

The operating fluid is conveyed from the valve casing through the respective ports to each end of the cylinder to operate the piston or monkey by two preferably forked pipes 38 and 39. The forked ends 38^a of the pipe 38 are secured in any suitable manner to the valve casing so as to register with the passages 32 and 34. The pipe 38 is connected to the fluid passage 40 in the cylinder walls (Figs. 1 and 2), opening to the end of the cylinder, whilst the pipe 39 is connected to the passage 41, opening into the opposite end of the cylinder. 43 are cover plates bolted or otherwise suitably attached to the ends of the valve casing 23 in a fluid tight manner. 44 is an exhaust passage in the wall of the casing, for the fluid operating the valve whilst 45, 45, are exhaust ports in the casing for the piston operating fluid, said ports being preferably located opposite to one of the forked ends, 38^a or 39^a of the pipes 38 and 39 respectively.

The operation is as follows:

The valve chamber 35 is supplied with steam or other operating fluid through a pipe or pipes connected to the port 36. Part of the fluid passes through the passage 16 and one of the ports 15 to the annular chamber 14, formed in the piston or monkey. Now assuming the piston to be in the position shown in Fig. 1, the steam passes from the chamber 14, through the passage 19 in the cylinder walls, through the port 27^a from which it

impinges against the walls of the pockets 27 in the disc 24. The disc being connected to the valve spindle, the valve is rotated opening the passage way 33, to the chamber 35, in the valve casing and simultaneously closing 70 the exhaust passage 31. At the same time the passages, 32 and 34 are also reversed from the position shown in Fig. 3. The steam now passes through the passage 33, pipe 38, through the passage 40 in the walls of the cylinder beneath the piston causing the latter to rise within the cylinder. In rising the passage of the steam to the pockets 27, in the disc 24 is cut off owing to the piston covering the passage 19.

The piston now rises until the chamber 14, therein comes opposite to one of the ports 20, the cock 21, of which is in its open position, in Figs. 1 and 2 it is assumed that the uppermost port 20 is open whilst the two intermediate ports are closed. The piston has now reached the position shown in Fig. 2, and steam is forced through the passage 19^a from which it is transmitted to the valve casing and enters a corresponding port registering with the pockets 27 in the disc 25. The valve is now rotated in the opposite direction causing the passage 33 to be closed whereby the steam is cut off from the underside of the piston whilst simultaneously the passage 31 is opened to exhaust through the port 35, as shown in Fig. 3. This rotation of the valve also places the chamber 35 in the valve casing in communication with the top of the cylinder through the passage 32, pipe 39 and the passageway 41, in the walls of the cylinder the fluid entering above the piston under pressure forcing the piston down until it strikes the striking block 4, the lower end of the cylinder exhausting through the passage 40, in the cylinder walls, pipe 38, passageway 31, and thence through the port 45, to the atmosphere. When the piston again rises, the exhaust from the chamber above the piston is exhausted through the passage 41, pipe 39, passage 34, in the valve spindle and thence through the port 45 to the atmosphere.

When the valve is rotated the fluid escapes through the passageway 30 extending across each of the discs 24 and 25, the fluid reaching the circumferential slot 28, just before the valve has been rotated to its maximum extent, by this means a cushioning effect is produced between the end 28^a of the passage 28 and the slot 29, the fluid finally discharging through the port 44.

The discs 24 and 25 on the ends of the valve spindle may, if necessary be formed with passageways 49 communicating with the exhaust passages 31 and 34, respectively through which the fluid for operating the valve escapes.

The cylinder is provided with two or more

longitudinal rods or bars 51, shown in chain lines in Fig. 1. These rods are formed with eyes, hooks, rings, or the like at each end preferably passed through holes or perforations in the cover plate 3, the flanged end 2 and an annular flange 50, located a short distance from the opposite end of the cylinder. When the apparatus is used for pile driving or the like operations, the machine is supported by chains, cables or the like, from the members 52^a whilst when the machine is to be used for pile extracting, it is merely necessary to invert the machine so that the members 52 become uppermost whilst the grips of other tackle are screwed on to the end 12 of the central shaft and the apparatus is ready for operation.

In the construction shown in Fig. 5, the central rod 7^a on which the piston slides is made hollow to serve as a passage 53 for the admission of operating fluid. This passage is provided with two longitudinal slots 54, 55, whilst the piston or monkey 13 is provided with two radial ports 56, 57 communicating with the annular chamber 14. The cylinder cover plate 3 may be provided with a suitable casing 58 connected to a suitable source of supply of operating fluid, the hollow rod 7^a having a port 59 communicating with the interior of said casing as will be readily understood. In some cases the end of the hollow rod 7^a may be connected direct to a pipe through which operating fluid is supplied.

In some cases I may provide two hollow rods one of which is capable of being rotated and locked in any adjusted position with relation to the other as shown in Fig. 6. In this construction the outer hollow rod 60 is formed integral with or attached to the anvil block 4 and is provided with a series of ports 61, spaced apart longitudinally of the rod. Within this rod is mounted a partly hollow rod 62, provided with ports 63 arranged at spaced intervals apart but each displaced angularly relatively to one another. The piston or monkey 13 which is a sliding fit on the outer tube or rod 60 is provided with an inner annular chamber 64 communicating with the outer annular chamber 14 through one or more radial passages 64^a. The lower end of the rod 62 is formed with a head 65 which may be formed square or any other shape according to the number of ports, adapted to engage a correspondingly shaped recess 66 closed by a screwed plug 67 or other suitable means. In Fig. 6, the inner hollow rod is in a position in which its uppermost port 63 registers with the uppermost port 61 of the outer rod 60. The lower end of the rod 62 is provided with ports 68 arranged in the same transverse plane but displaced angularly relatively to one another by 90°. These ports register with a port 61^a in the outer rod 60. With the construction

shown the valve operating fluid is admitted through the inner rod 62 and passes through the ports 68 and 61^a to the annular chamber 64 thence to the outer chamber 14 to the passage 19 and thence to the valve. The latter is now reversed causing the operating fluid to be transmitted through the passage 40 to the lower end of the cylinder. The piston or monkey 13 is now moved upwardly to the position shown in dotted lines. As soon as the upper end of the inner chamber 64 registers with the uppermost port 61 (or any other port which is open), the valve operating fluid is placed in communication with and reverses the valve through the passages 63 and 61, chamber 64, passage 64^a, chamber 14, passage 20^a to the valve chamber.

Fig. 7 shows a modified construction of piston or monkey, in which its outer periphery is formed with two annular chambers 14^a co-operating with the inlet ports 15 and the passages leading to the valve chamber. The operation is similar to that first described and needs no further description.

In the construction shown in Fig. 8, the central rod and the annular chamber in the piston 13, are dispensed with. In this form the cylinder walls are provided with passages 68, 69 leading to ports arranged at opposite ends of the cylinder. Between the ports, passages 70, 71 are provided which are located in such a position that they are alternately uncovered by the piston 13 on the latter reaching the end of its stroke, or preferably immediately before it reaches these positions. The operation will be readily understood. The passages being connected to the valve chamber steam is transmitted say to the passage 69, the passage 68 being open to exhaust when the piston is in the position shown in Fig. 8. The piston is now raised by the fluid admitted to its underside. As soon as the lower end of the piston 13 uncovers the passage 71, the fluid is admitted to one of the passages 27^a of the valve whereby the latter is rotated to its reverse position, the passage 69 being opened to exhaust whilst the passage 68 is opened to the admission of fluid above the piston. The latter now moves downwardly until the passage 70 is uncovered by the upper end of the piston whereby the valve is again reversed.

In general the invention may be modified in various ways without departing from the principle thereof.

What I claim as my invention and desire to secure by Letters Patent of the United States of America is:—

1. Apparatus for controlling the movement of pistons for operating pile drivers, pile extractors, hammers, and the like apparatus, comprising a cylinder, passages in said cylinder communicating with a valve

- chamber, a plurality of separately closable ports arranged longitudinally of said cylinder and communicating with one of said passages, a piston or monkey reciprocating 5 within said cylinder, at least one annular chamber, in the periphery of said piston co-operating with said ports, a valve rotatably mounted in said valve chamber, discs on the ends of said valve, peripheral pockets dis- 10 posed in opposite directions in each of said discs against which operating fluid is directed through passages in said cylinder, and transverse ports in said valve through which the operating fluid is alternately ad- 15 mitted to and emitted from opposite ends of said cylinder.
2. Apparatus for controlling the movement of pistons for operating pile drivers, pile extractors, hammers and the like appa- 20 ratus, comprising a cylinder, passages in said cylinder communicating with a valve
- chamber, a plurality of separately closable ports arranged longitudinally of said cylinder and communicating with one of said passages, a piston or monkey reciprocating 25 within said cylinder, at least one annular chamber in the periphery of said piston co-operating with said ports, a valve rotatably mounted in said valve chamber, discs on the ends of said valve, peripheral pockets in 30 each of said discs, circumferential slots in the discs located diametrically opposite said pockets, a passage between said slot and the said pocket in each disc, a stop extending into said slots to limit the rotary movement 35 of said valve and transverse ports in said valve through which the operating fluid is alternately admitted to and emitted from opposite ends of said cylinder.

In testimony whereof I affix my signature.

RICHARD HENRY ANNISON.
